INVENTOR:

Karl Stahl.

UNITED STATES PATENT OFFICE.

KARL STAHL, OF FRIEDRICHSHAFEN, GERMANY, ASSIGNOR TO THE FIRM: LUFT-SCHIFFBAU ZEPPELIN GESELLSCHAFT MIT BESCHRÄNKTER HAFTUNG, OF FRIEDRICHSHAFEN, GERMANY.

BALLAST CONTAINER FOR AIRCRAFT.

1,418,491.

Specification of Letters Patent. Patented June 6, 1922.

Application filed June 28, 1920. Serial No. 392,602.

To all whom it may concern:

Be it known that I, KARL STAHL, German citizen, residing at Friedrichshafen, Germany, have invented certain new and useful 5 Improvements in Ballast Containers for Aircraft (for which I have filed an application in Germany, June 3, 1918), of which the following is a specification.

My invention relates to containers for 10 liquid and fine-grained solid substances adapted to be quickly emptied. It refers more particularly to the construction and the provision of an emptying device in connection with the containers used for holding 15 the ballast required for airships.

Ballast containers in the shape of barrels, bags, etc., are already employed for aircraft. However, barrels, even when empty, take up much room, while the containers 20 consisting of a woven fabric, or the like, so far known, possess no emptying device which may be considered as absolutely reliable.

Besides, owing to their height being limited, it is always necessary to set up or suspend these containers at certain definite places, in themselves not infrequently very unfavourably located.

It is an object of this invention to produce a ballast-containing device composed of one or more parts, of low cost of manufacture, great strength, extremely light weight, and provided moreover with a reliably operating emptying arrangement, and 35 which lastly may not only be suspended at any point of the airship but may also be operated from any part of the vessel desired.

The subject matter of this invention accordingly has reference to a ballast container, in particular for the liquid ballast of airships, adapted to be quickly emptied, and in which a sack or bag-shaped container terminates at the bottom in a leg-shaped outlet. Subject to this invention, this outlet portion may be turned up, and when the container is filled it will reach to about the upper edge of the container. On this tucked up end being then let down, the entire contents of the container will almost immediately be discharged.

Now since the length of the outlet member, connected to the bottom portion of the container proper, which in width is essen-

tially narrower than the said container when 55 completely filled, approximately equals the height of this said container, this latter may be hung up very high in the airship at a place, where it will be in no one's way. Again, if two such containers or receptacles 60 be hung up so closely next to each other that their broad sides, when the containers are filled, will just come to touch, and if the height selected for the container proper be just three quarters the size of a man, then 65 there will be left space enough between the substantially narrower outlet portions to allow a person to pass through conveniently.

To prevent any ballast from being flung about the airship by the outlet member as it 70 is being let down for the purpose of emptying the ballast, there is provided—and this is an additional feature of my invention—at the bottom of the container proper, besides the aforesaid outlet, an additional 75 guide member enveloping the outlet and having likewise the shape of a leg. The lower end of this guide member is suitably fixed to a funnel-shaped rigid outlet connection having a resilient joint flap, the 80 outer end of which terminates in a line with the outer skin of the airship. To obviate the necessity of storing up in one single container too large quantities of ballast, which would have to be emptied at one operation, 85 use is preferably made of an arrangement consisting of a plurality of parts, in the case of which a ballast receptacle, subdivided by one or more partitions into a plurality of chambers, is provided at the bottom of each 90 of said chambers with an outlet member adapted to be either tucked up or drawn up. To simplify the arrangement, there is only provided a single guide member, serving as the common guide for all the outlets, and 95 which branches off from the container at or shortly beyond the point where the container passes over into the outlets, and which envelops these latter.

Further to prevent the single outlet members, which as a rule will be let down in succession, but which, if required, may also be let down simultaneously, from interfering with each other, it will prove expedient to continue the partitions of the container proper 100 within the guide member so far downwards that they will at least approximately extend to the outlet connection. On the other

hand they are not continued in the upward direction right up to the upper edge of the container, but are provided shortly below said edge with overflow ports, to enable the 5 entire container to be filled from one particular place.

The device for suspending and releasing the outlets which, as said, may be either turned up or drawn up, may be of any kind 10 desired. Notwithstanding it will be found expedient to provide a releasing bar for securing the unattached ends of the outlet members, which for their part and to this end are provided with eyes. This releasing 15 bar is then connected on the one hand to a vertically shiftable support having a horizontal linked axis and resting, on the other hand, when the support assumes its lower-most position, with its unattached end on an 20 immovable support. For in such an event, by merely drawing up the displaceable support or bearing, the releasing bar will without any doubt be shifted into an incline, and will be drawn off from the stationary bearing. 25 This causes the links or eyes to glide off from the releasing bar, so that the outlet ends will drop down.

To afford the possibility of successively emptying ballast containing arrangements 30 comprising a plurality of parts, with the help of but a single tension member, the movable bearing of each releasing bar is connected each to a bent lever; in which case the unsupported shank of each of these 35 levers is disposed within the part of a series of stops fixed at regular intervals to a common tension member, say, a wire, and serving for an entire ballast containing arrangement comprising a plurality of parts.

40 An embodiment of the subject matter of the invention is shown in a purely diagrammatic manner by way of example in the accompanying drawing, in which:

Figs. 1 and 2 are a longitudinal section 45 and side view, respectively, of a two-part ballast containing arrangement on a large scale,

50 Fig. 3 a side view of a detail, showing the method of suspending and releasing the outlet portions, and

Fig. 4 a cross section along line 4—4 in Fig. 3.

A ballast containing bag B is tied, and suspended to a tube A, said bag substantially 55 consisting of a bottom b' , two front faces b^2 , and two lateral faces b^3 . The upper edges of the lateral faces b^3 , which are provided with a series of eyes b^4 , are in addition fitted out close to their centre with two openings 60 b^5 for the accommodation of two releasing devices which will be described hereinafter. The bottom b' is also provided with two large openings, which adjoin each other, to the edges of which there are connected two 65 leg-shaped outlet members C and C'. At

their unattached ends, these members C and C' (the length of which approximately corresponds to the height of the bag) are provided with eyes C'. At the point where the bottom b' of the bag passes over into the 70 outlets, there is attached a common guide member F, so as to be perfectly liquid tight, and which envelops said outlet members, while at the same time being joined to a funnel-shaped outlet connection E. This 75 latter, which extends to the outer skin E' of the airship, is adapted to support at its unattached end a joint flap e' , attached by means of a hinge e^2 , and which, when not loaded, is kept closed by the action of a 80 spring e^3 . A partition to which at its upper half is water-tightly connected with the side faces b^3 of the ballast containing bag, and at its lower portion with the guide member D, divides the ballast containing bag, respectively, 85 into two chambers. To enable the bag to be filled from a particular point, the partition is not carried right through to the very top.

The releasing device for each half of the 90 bag is housed in a supporting plate F surrounding in the manner of a clamp, a tube A, the two halves or sections, of which said plate is composed being provided each with two laps f' and f^2 . The laps f' are at their 95 lower end connected in the manner of a strap by a stop f^3 . Intermediate the laps f^2 there is arranged to move the forked end g' of a releasing bar G, which with its other end reposes on the stop f^3 . On this bar the 100 tucked up end of the outlet members C or C' may be strung by aid of the eyes c' , as indicated in dotted lines in Fig. 1. A linked axis h' , adapted to shift within the vertical slots f^4 of laps f^2 , serves to unite the forked 105 end g' with a bearing H, linked at its other end to a bent lever J flexibly lodged intermediate the laps f^2 . The unattached end of the lever J is provided with an opening i' for the passage of a wire K. This latter embodies a stop K' for each section of the 110 ballast containing bag. If, as shown in Fig. 3 one of the stops K' comes to strike against the end of the bent lever, and if the wire K be moved in the direction indicated by the 115 arrow u , then the bent lever T will turn counter clockwise, the right hand end g' of the bar will be raised, and the bar G consequently be set at an incline, in order to finally depart from the stop f^3 and perpendicularly drop downwards. At this the eye c' will glide off from the bar, and the outlet member C or C', drawn up in front of the bag, impelled by its own weight as well as by the pressure of the water or sand contained in it will likewise drop down, so that this entire section of the container will be almost immediately emptied. During this operation the guide piece D prevents, in the one hand, the ballast from being flung or 125 130

squirted about the deck of the airship; on the other hand, it serves to take up the shocks caused at the moment when the bag was emptied by the ballast masses as they are 5 precipitated.

After the bags have been emptied of their contents, the outlet pieces C and C', respectively, may be drawn up in front of the guide member, respectively, the ballast containing 10 bag B proper, they being then strung up by aid of the eyes c' on the bars G, and these last returned into their locking position. As the guide member D would more or less prevent direct contact with the depending ends 15 C' of the outlet members, some of the eyes c' are interconnected by means of diagonally arranged cords, not shown in the drawing. By means of a hook, adapted to be lowered and raised by means of a string into the 20 ballast containing bag, respectively, into each of the outlet members C or C', the said cords may be caught and drawn up as far as the bars G. As soon as the eyes c' are strung up on the bars G, and the latter again 25 returned into their final position, the device is again ready to be filled.

I claim:

1. A ballast container comprising in combination, a bag, a hose of large section extending from an opening in the bottom of 30 said bag and means for releasably fastening the free edge of said hose inside said bag and in the upper part thereof.

2. A ballast container comprising in combination, a bag, a hose of large section ex- 35 tending from an opening in the bottom of said bag, means for releasably fastening the free edge of said hose inside said bag and in the upper part thereof, an envelope surrounding said hose and a valve in the lower 40 end of said envelope.

3. A ballast container comprising in combination, a bag, a plurality of hoses of large diameter extending from openings in the bottom of said bag, means for releasably 45 fastening the free edges of said hose inside said bag and in the upper part thereof, an envelope surrounding all said hose and a valve in the lower end of said envelope.

In testimony hereof I affix my signature. 50

KARL STAHL.
